UNITED STATES PATENT OFFICE.

HENRY S. DODD, OF TORONTO, ONTARIO, CANADA, ASSIGNOR OF ONE-HALF TO JOHN O'NEILL, OF TORONTO, ONTARIO, CANADA.

HEATER.

1,375,137.

Specification of Letters Patent. Patented Apr. 19, 1921.

Application filed May 14, 1918. Serial No. 234,563.

To all whom it may concern:

Be it known that I, HENRY STANSFIELD DODD, of 313 Eglinton avenue, in the city of Toronto, county of York, Province of Ontario, Canada, a subject of the King of Great Britain, have invented certain new and useful Improvements in Heaters, of which the following is a specification.

This invention relates to heaters particularly adapted for the heating of a circulating fluid such as air or water, or for the generation of steam, and my object is to devise a heater for this purpose in which a gaseous fuel can be economically used.

I attain my object by means of the constructions hereinafter described and illustrated in the accompanying drawings in which—

Figure 1 is a vertical section of a heater constructed in accordance with my invention; and

Fig. 2 a cross section on the line *a—a* in Fig. 1; and

Fig. 3 a vertical section showing a modification of the closure 4 shown in Fig. 1.

In the drawings like numerals of reference indicate corresponding parts in the different figures.

The device, as usual in heaters of this kind, employs a combustion chamber and radiating system which, when a heating fluid is to be circulated, is surrounded by a casing. The casing in the present construction is preferably formed in three sections 1, 2 and 3. The upper section is provided with the outlet 5 and the lower section with the inlet 6. The middle section of the casing contains the combustion chamber 9, which is provided with a central tubular extension 42 which reaches up through the upper section and passes through an opening therein, a suitable tight joint being formed between the parts by the gland 41.

The upper end of the chamber 9 has a cover 10 with a pipe 40 connected therewith, which pipe is formed with an elbow having an opening in its end inclined somewhat from the vertical away from the hanging closure 4, which, when there is no suction in the combustion chamber, hangs straight down so that the products of combustion from the pilot light may pass away. As soon as suction exists the light flap is drawn inwardly to close the opening. A suitable flue 50 is connected with this pipe.

Through the side of the combustion chamber is formed a lateral extension communicating with a tube 34 extending through a boss 35 formed on the wall of the section 2 of the casing. A gland 36 is employed to prevent leakage around the tube, while permitting endwise movement of the tube. The gland has an open end 11, provided with a transparent closure 7. Through the tube the pilot light may be lit. Access to the burner 8 is readily had or the latter placed in position or removed by removing the cover 10 from the top of the combustion chamber. The under side of the combustion chamber is preferably formed of a removable plate 12. The combustion chamber is provided with lugs 38 by means of which it is supported on lugs 39 formed on the lower part 3 of the casing, but is not secured thereto in any way.

The radiating system includes concentric tubes 13 and 14. The tubes 13 extend into openings in the top of the combustion chamber leading to the interior of the upper section 1. The tubes 14 extend from the openings in the plate 12 to openings in the top of the header 15. The lower ends of the tubes 13 are connected with openings in the bottom of the header 15. The products of combustion thus pass from the combustion chamber between the inner and outer tubes into the header 15. From this header 15 extends the exhaust flue 16, which extends through the lower section 3 of the casing preferably concentric with the vertical axis 90 of the heater.

The opening in the end of the casing through which the exhaust flue passes is made water and steam tight by a suitable stuffing box 17. The object of this arrangement is to prevent any strain on the radiating system which would result in leakage. The radiating system, which includes the combustion chamber 9, tubular extension 10, tubes 13 and 14, header 15 and part of the exhaust flue 16, is subjected at times to sudden changes of temperature which causes its expansion or contraction more rapidly than the expansion or contraction of the casing, and as with the construction shown the radiating system is merely supported on the casing by means of the combustion chamber and is otherwise free, its expansion and contraction is quite independent of the contraction and expansion of the casing. The ex-

haust flue connects by means of the pipe 18 with an exhaust pump 19. When the device is in operation the pump is run to suck the burnt gases from the combustion chamber and radiating system of the heater. Very intense combustion then takes place in the combustion chamber of the mixture of air and gas supplied to the burner and very rapid expansion of the products of combustion at once takes place, resulting in a slight pressure in the combustion chamber.

The spaces between the tubes are, however, sufficient in area to permit of the immediate expansion of these gases. Owing to the suction, combustion takes place not only in the combustion chamber, but also in the spaces between the tubes where the greatest transfer of heat to the fluid to be heated will take place. The greatest difference exists here between the temperature of the fluid to be heated and the heat transferring surfaces.

The fire tubes are comparatively long and compensation is thus obtained for their small cross sectional area compared with that of the combustion chamber. By the time the products of combustion reach the exhaust flue outside the casing they have been cooled substantially to the temperature of the fluid entering the casing from the return pipe. The burner 8 is located within the combustion chamber as shown and may be of any form. I prefer, however, to employ a burner of cylindrical form having disk-shaped ends between which are set a series of bars between which a combustible mixture passes and outside which it ignites. Connected with the interior of the burner is the supply pipe 21. This passes down through the plate 12 and header 15 and through the exhaust flue 16 and is provided at its end with a connection 22.

Where the supply pipe passes through the elbow-shaped stuffing box 17, a packing gland 23 is provided. The gas is mixed with air in a mixing chamber 30 of which 31 is the air inlet and 32 the gas inlet. The flow of gas will be controlled by means of any suitable automatic valve 33. A suitable valve for this purpose will be made the subject of a separate application. The valve is connected to the suction pipe 18 by means of the pipe 28. The purpose of the valve is to close off the gas supply whenever the suction ceases. The air inlet of the mixing chamber is connected by a pipe 24 with an air preheating chamber 25 surrounding the pipe 18. The space between the pipe and chamber is preferably provided with a spiral or other baffle 26 to cause the air to travel over as much of the surface of the warm pipe 18 as possible.

Gas to supply a pilot light may be led through a tube 27 which extends through a

supply pipe 21 and extends into the interior of the burner where it is provided with one or more branches 47 extending to the outside of the burner at one or more points.

In burning gas, water vapor is one of the products of combustion and provision must be made for its removal from the radiating system of the heater. For this purpose I provide the pipe 57 leading from the stuffing box 17, which pipe will be suitably trapped.

As the fluid returning to the casing through the return pipe 6 will seldom give a temperature of less than 160° Fahr. the exhaust gases will have at least the same temperature. Owing to the fact that I use a pump 19 to exhaust the gases from the heater, I am enabled to circulate these exhaust gases through a radiating coil 56 from which the remaining heat units are readily extracted and employed for heating or ventilating purposes.

When the heater is running and the burner alight, all the air required for the combustion of the gas is sucked through the mixing chamber 30. When the burner is out, the pump is stopped but sufficient air is drawn through by natural draft to maintain the pilot light at the branches 47.

A simple hanging closure such as shown in Fig. 1 does not always provide free enough exit for burnt gases and is somewhat liable to damage. I prefer therefore to use the specific construction shown in Fig. 3, which is identical, however, in mode of operation. The closure is formed as a plate 4^a adapted to seat on the opening 43 in the cover 10. A yoke 44 is suitably supported above the opening and carries the counterbalanced lever 45 to which is pivotally connected the connecting rod 46, which passes loosely through an opening in the plate 4^a and has a ball 58 formed at its lower end. The lever 45 is so weighted that normally it will raise the plate 4^a, but the balance will be so delicate that the plate is easily drawn down again when suction exists in the apparatus. If any explosion of gases takes place in the heater, this plate is driven up the connecting rod and free exit for the gases is provided. It will be noted that comparatively small lift of the plate gives a very free exit for the products of combustion from the pilot light.

My apparatus in operation is found to be exceedingly economical. It is also easily constructed and easily taken apart for repairs.

What I claim as my invention is:

1. A heater comprising a casing, an air pump, a combustion chamber located at one end of the casing above the bottom thereof, a radiating system with which the combustion chamber communicates and from which the products of combustion are drawn by

the air pump comprising a header located toward the other end of the casing, a plurality of fire tubes opening through the bottom of the combustion chamber below the 5 burner and connecting the combustion chamber and the header, an exhaust flue extending from the header through the adjacent end of the casing, a tube extending laterally from the combustion chamber through the 10 side of the casing, a suitable closure for the outer end of the tube, the exhaust flue arranged axially of the header and provided with a stuffing box in the end of the casing through which the exhaust flue passes, and 15 a supply pipe to the burner extending axially through the exhaust flue and passing through the wall of the flue outside the casing.

2. A heater comprising a casing, an air 20 pump, a combustion chamber located at one end of the casing above the bottom thereof, a radiating system with which the combustion chamber communicates and from which the products of combustion are drawn by the air 25 pump comprising a header located toward the other end of the casing, a plurality of fire tubes opening through the bottom of the combustion chamber below the burner and connecting the combustion chamber and the 30 header, an exhaust flue extending from the header through the adjacent end of the casing, a tube extending laterally from the combustion chamber through the side of the casing, a suitable closure for the outer end of 35 the tube, the exhaust flue arranged axially of the header and turned at an angle outside of the casing, and provided with a stuffing box in the end of the casing through which the exhaust flue passes, a supply pipe 40 to the burner extending axially through the exhaust flue, and a stuffing box, located in the wall of the flue at the bend, through which the supply pipe passes.

3. A heater comprising a casing, an air 45 pump, a combustion chamber located at one end of the casing above the bottom thereof, a radiating system with which the combustion chamber communicates and from which the products of combustion are drawn by 50 the air pump comprising a header located toward the other end of the casing, a plurality of fire tubes opening through the bottom of the combustion chamber below the burner and connecting the combustion chamber 55 and the header, an exhaust flue extending from the header through the adjacent end of the casing, a tube extending laterally from the combustion chamber through the side of the casing, a suitable closure for the 60 outer end of the tube, a tubular extension of the combustion chamber extending through the end of the casing, and a removable closure for said extension, the burner being removable through said extension.

4. A heater comprising a casing, an air

pump, a combustion chamber located at one end of the casing above the bottom thereof, a radiating system with which the combustion chamber communicates and from which the products of combustion are drawn by 70 the air pump comprising a header located toward the other end of the casing, a plurality of fire tubes opening through the bottom of the combustion chamber below the burner and connecting the combustion 75 chamber and the header, an exhaust flue extending from the header through the adjacent end of the casing, a tube extending laterally from the combustion chamber through the side of the casing, a suitable closure for the outer end of the tube, the casing being divided into three or more horizontal sections, the middle section containing the combustion chamber and in which the combustion chamber is provided with a 80 part extending through the end of the upper section and with a suitable removable closure for the upper end of said part.

5. A heater comprising a casing divided into three sections; a combustion chamber 90 contained in the middle section and provided with lugs, the lower section being provided with lugs at its upper end on which the lugs of the combustion chamber rest; an upward extension of the combustion 95 chamber extending through the top of the upper section and provided with a suitable closure; a fuel burner located within the combustion chamber; and a radiating system with which the combustion chamber 100 communicates and from which the products of combustion are drawn by an air pump comprising a header located toward the other end of the casing; a plurality of fire tubes connecting the combustion chamber 105 and the header and an exhaust flue extending from the header through the adjacent end of the casing.

6. In a heater, the combination of a casing for the fluid to be heated provided with an inlet and outlet; and a radiating system within the casing freely suspended on the casing so as to be free to expand laterally, the said radiating system including a combustion chamber adjacent its upper end, an upward extension of the combustion chamber passing through the upper end of the casing and an exhaust flue extending down through the lower end of the casing; and stuffing boxes adapted to make tight joints 115 where the exhaust flue and the extension pass through the casing.

7. In a heater, the combination of a casing comprising a lower, an intermediate and an upper section, lugs at the upper end of the lower section; a combustion chamber provided with lugs adapted to rest on the lugs aforesaid; an inspection tube extending from the side of the combustion chamber and passing through the side of the in- 125

termediate section; and a stuffing box adapted to make a tight joint where the tube passes through said section.

8. In a heater, the combination of a casing for the fluid to be heated provided with an inlet and an outlet; a combustion chamber within the casing freely suspended on the casing; an inspection tube extending from the side of the combustion chamber 10 and passing through the side of the intermediate section; and a stuffing box adapted to make a tight joint where the tube passes through said section.

9. In a heater, the combination of a casing for the fluid to be heated provided with an inlet and an outlet; a combustion chamber within the casing freely suspended on the casing; an inspection tube extending from the side of the combustion chamber 20 and passing through the side of the intermediate section; a stuffing box adapted to make a tight joint where the tube passes through said section; and a transparent closure for the open end of the stuffing box.

25 10. A heater comprising a casing, an air pump, a combustion chamber located at one end of the casing above the bottom thereof,

a radiating system with which the combustion chamber communicates and from which the products of combustion are drawn by 30 the air pump comprising a header located toward the other end of the casing, a plurality of fire tubes opening through the bottom of the combustion chamber below the burner and connecting the combustion chamber and the header, an exhaust flue extending from the header through the adjacent end of the casing, a tube extending laterally from the combustion chamber through the side of the casing, a suitable closure for the 35 outer end of the tube, a tubular extension of the combustion chamber extending through the end of the casing, a removable closure for said extension, the burner being removable through said extension, an outlet from 40 the cover, and a closure for the outlet normally tending to remain open a predetermined distance and movable under the influence of suction within the heater to close the outlet. 45

Signed at Toronto, Canada, this 1st day of May, 1918.

HENRY S. DODD.
